UNITED STATES PATENT OFFICE.

LEONARD ALFRED LAMAR, OF PORTLAND, OREGON.

SUBMARINE.

1,271,513.

Specification of Letters Patent.

Patented July 2, 1918.

Application filed April 2, 1917. Serial No. 159,287.

To all whom it may concern:

Be it known that I, LEONARD A. LAMAR, a citizen of the United States of America, residing at Portland, in the county of Multnomah and State of Oregon, have invented 5 certain new and useful Improvements in Submarines, of which the following is a specification, reference being had therein to the accompanying drawing.

10 This invention relates to a submarine and has for its principal object the production of a submarine wherein simple and efficient means is positioned thereon for facilitating the passage of the submarine through nets and like obstructions and for also increasing 15 the speed of the submarine.

Another object of this invention is the production of a submarine wherein a rotatable sleeve is positioned upon the forward 20 end of the hull of the submarine in such manner as to permit rotary motion to be imparted to the sleeve so as to cause a spiral fixedly mounted upon the sleeve to draw the submarine through a net or like obstruction 25 and for also increasing the speed of the submarine.

A still further object of this invention is the production of a submarine wherein a movable observation tower is carried there- 30 by in such manner as to permit the tower to extend above the hull of the submarine when the same is not encountering any obstructions but which can be lowered into the hull of the submarine when the submarine is 35 passing through a net or like obstruction.

With these and other objects in view this invention consists of certain novel combinations, constructions and arrangements of parts as will be hereinafter fully described 40 and claimed.

In the accompanying drawings;—

Figure 1 is a side elevation of the submarine as constructed in accordance with this invention;

45 Fig. 2 is a central longitudinal section through the forward end of the submarine showing the rotatable sleeve carried thereby;

Fig. 3 is a vertical section through the submarine a portion of the observation tower 50 being broken away;

Fig. 4 is a horizontal longitudinal section through a portion of the submarine and the observation tower illustrating the raising and lowering means for this tower;

55 Fig. 5 is a central vertical section through a portion of the hull of the submarine and

the observation tower, showing the obser- vation tower in a raised position;

Fig. 6 is a transverse section through a portion of the hull of the submarine and the 60 shell mounted thereon, showing the roller bearing race in elevation;

Fig. 7 is a transverse section through the roller bearing race showing one of the rollers in elevation and illustrating the manner 65 in which the rear portion of the shell of the sleeve is supported upon the hull of the submarine;

Fig. 8 is a reduced section taken on the line 8—8 of Fig. 7. 70

Referring to the accompanying drawings by numerals it will be seen that 1 designates in general the hull of a submarine which of course can be of any desired shape or size. This hull 1 is provided with the usual keel 75 2 and propeller 3 adjacent which is carried the rudder 4.

The sleeve 5 is substantially conical in shape as illustrated clearly in Fig. 2 and this sleeve 5 is adapted to be positioned over 80 the forward end of the hull 1 of the submarine since the forward end of the hull should be substantially conical in order to receive the sleeve 5 and to permit the sleeve to rotate therearound. The roller bearing course 85 comprises a body 6 having spaced parallel flanges 7 extending therefrom and this body 6 is retained by rivets 8 in a fixed position within the sleeve 5. It will be noted that one of the flanges 7 is broader than the re- 90 maining flange 7 as illustrated in Fig. 7 so that the larger of the two flanges may engage the outer surface of the hull 1 of the submarine for preventing the passage of wa- 95 ter into the interior of the sleeve 5. This 95 roller bearing course is circular and extends entirely around the hull 1 of the submarine as is evidenced by the construction shown in Fig. 6. The roller bearings 9 have pins 10 projecting from their ends and engaging the 100 flanges 7 so as to cause the roller bearings to be held from wedging within the roller bearing race when the sleeve 5 is rotated. Since the roller bearings 9 fit upon the outer 105 surface of the hull 1 of the submarine it is ob- 110 vious that when the sleeve 5 is rotating the friction will be greatly reduced since these roller bearings 9 will ride evenly and prevent a frictional action upon the hull of the submarine.

The drive shaft 11 extends from the engine which propels the submarine and ex-

tends through the brace 12 carried within the hull 1 by the submarine as shown in Fig. 2 whereby the drive shaft 11 will be sufficiently reinforced intermediate its ends. This drive 5 shaft 11 has its squared forward end 13 projecting beyond the forward end of the hull 1 so as to engage the head 14. This head 14 is riveted as indicated at 15 to the offset collar 16 formed upon the forward end of the 10 sleeve 5. It is therefore obvious that as the drive shaft 11 is rotated the squared forward end 13 thereof will impart rotary motion to the head 14 and this head 13 in turn will impart rotary motion to the sleeve 5.

15 The ribbon like spiral 17 is formed upon or secured in any desired or suitable manner to the exterior of the sleeve 5 extending from the head 14 to the rear end of the sleeve 5 as shown in Figs. 1 and 2. It is therefore 20 obvious that as rotary motion is imparted to the sleeve 5 the spiral like construction of the ribbon spiral will cause this spiral to assist in drawing the submarine through the water which action coupled with the propul- 25 sion of the submarine by the propeller 3 will increase the speed of the submarine. Furthermore the pointed head 14 when coming into engagement with a net or like obstruction will pierce the same so as to per- 30 mit the spiral 17 to pass into the opening thus formed into the obstruction and as the sleeve 5 rotates the spiral will act in a screw like manner for drawing the submarine through the net or other obstruction. The 35 increased size of the conical sleeve 5 will increase the size of the opening while the spiral 17 will draw the submarine through the obstruction.

The observation tower 18 is provided with 40 double walls 19 formed thereon as shown clearly in Figs. 4 and 5 so as to provide chambers 20 adjacent each side of the obser- 45 vation tower. This observation tower 18 is provided with a curved top 21 which curves at substantially the same angle as the hull 1 of the submarine so that when the observation 50 tower is in a lowered position the top 21 will fit snugly upon the outer surface of the hull 1 of the submarine for presenting a sub- 55 stantially even outer surface which will not strike into the surface through which the submarine is passing. It is of course obvious that the observation tower 18 may be pro- 60 vided with side openings 22 closed by the glass quartz 23 held by the retaining frames 24 as illustrated clearly in Fig. 5. As the walls 19 are provided with side openings 22 in alinement with the outer side openings a clear view may be obtained upon either side 65 of the observation tower.

In order to raise or lower this observation tower elongated racks 25 are carried upon the inner walls 19 within the chambers 20. The platform 26 positioned within the hull 1 of the submarine carries standards 27

which project into the lower ends of the chambers 20 of the observation tower. The upper ends of the standards 27 are provided with journals 28 carrying the stub axles 29 upon which pinions 30 are keyed in any suitable manner. These pinions 30 engage the racks 25 so that when rotary motion is imparted to the pinions 30 the observation tower 18 will be either raised or lowered. Upon the stub axles 29 are also keyed 70 sprocket wheels 31 around which pass the chains 32, these chains 32 also engaging sprocket wheels 33 carried by the shaft 34 connected to the gears 35. These gears 35 mesh with gears 36 of the driving motors 37 so that when the gears 36 are rotated by the 80 motors 37 rotary motion will be imparted to the gears 35. As the gears 35 are rotated the sprockets 33 will be rotated, thus causing the chains 32 to drive the sprockets 31. As the sprockets 31 are driven rotary motion will be imparted through the stub axles 39 to the pinions 30 so that these pinions 30 by acting upon the racks 35 will either raise or lower the observation tower. Under normal 90 conditions this observation tower is in a raised position as illustrated in Figs. 1 and 5 so as to permit the operators of the submarine to easily direct the ship. If however the submarine is about to pass through a net or some like obstruction the motors 37 are operated so as to cause the pinions 30 to rotate in such a manner as to permit the racks 25 to move downwardly in unison with the downward movement of the observation 100 tower 18. When the observation tower 18 moves downwardly into the interior of the submarine the top 21 may fit snugly upon the outer surface of the hull 1 of the submarine so as to present a substantially even outer 105 surface if desired or the movement of the observation tower downward may be limited when the tower assumes the position illustrated in Figs. 3 and 5 thereby permitting the side openings to be slightly above the outer side of the hull 1 of the submarine.

It is of course obvious that any suitable means other than the means disclosed herein may be employed for raising and lowering the observation tower, such for instance as gas, compressed air, steam or manual power, while the specific connections may also be different without departing from the spirit of the invention since the principal object in connection with the observation tower is the provision of a tower which may be raised or lowered as the occasion may require.

From the foregoing description it will be seen that a very efficient submarine has been disclosed which has a rotatable sleeve upon its forward portion on which is mounted a spiral constructed so as to increase the speed of the submarine and also facilitate the drawing of the submarine through an obstruction while the observation tower may 130

be normally in a raised position for facilitating the maneuvering of the ship by the operator thereof, although this tower may be moved to a lowered position for allowing 5 the submarine to pass through an obstruction which could not be done if the tower remained in a raised position.

It is not desired to limit the construction 10 of this invention to the specific form as herein shown, but to include all such forms 15 of the device as properly come within the scope of the invention as claimed.

What is claimed, is:—

1. In a submarine of the class described, 15 the combination with the hull, of a rotatable nose-sleeve mounted upon one end thereof, the inner end of the nose-sleeve terminating short of the middle of the hull, an annular roller bearing body secured within said 20 sleeve at its inner end, said body provided with an outer annular flange engaging the outer face of the hull, constituting a closure for the compartment formed between the hull and the sleeve, roller bearings in said 25 body, and each bearing engaging said flange, and means for imparting rotary motion to said sleeve.

2. In a submarine of the class described, 30 the combination with a hull, of a nose-sleeve positioned upon one end of said hull, a roller bearing body between said hull and sleeve at the inner end of said sleeve, said body provided with outer and inner parallel flanges, said hull and sleeve having a com-

partment formed between the same, said 35 outer flange of the roller bearing body closing the outer end of said compartment, said flange having its outer face in the same vertical plane with the inner end of the sleeve, the inner flange of the body being of less 40 width than the distance between the hull and the sleeve for permitting any foreign substance to pass out of the roller bearing body and into the compartment formed between said hull and sleeve, bearings in said 45 body, fastening means extending through a portion of the body and through said sleeve for securing the bearing body in position at the extreme inner end of the sleeve, and means for imparting rotary movement to 50 said sleeve.

3. In a submarine, the combination with a hull, of a nose-sleeve on the front end of said hull, said nose-sleeve having its inner end terminating short of the central portion 55 of the hull, a bearing device positioned between the hull and the sleeve, at the inner end of said sleeve, and the outer end of the bearing device positioned in the same vertical plane with the outer end of the sleeve, 60 a compartment formed between the hull and the sleeve, the bearing device closing the outer end of said compartment, and means for imparting rotary movement to said sleeve. 65

In testimony whereof I hereunto affix my signature.

LEONARD ALFRED LAMAR.
